UNITED STATES PATENT OFFICE.

MARTIN THORSEN RELLING, OF BUTLER, PENNSYLVANIA.

SEAL FOR CAR-DOORS.

1,270,869.

Specification of Letters Patent.

Patented July 2, 1918.

Original application filed June 8, 1915, Serial No. 32,967. Divided and this application filed January 25, 1916. Serial No. 74,159.

To all whom it may concern:

Be it known that I, MARTIN THORSEN RELLING, a citizen of the United States, residing at Butler, in the county of Butler and State of Pennsylvania, have invented certain new and useful Improvements in Seals for Car-Doors, of which the following is a specification.

This invention relates to a seal for car doors, more particularly doors for refrigerator cars, and is a division of my application filed June 8th, 1915, Serial No. 32967, and besides the object set forth in the application referred to a further object is to provide, in a manner as hereinafter set forth, a sliding car door, more particularly for use in connection with refrigerator cars, or for other purposes wherein it is found applicable, with means for setting up a seal between the door and the door frame when the door is in a position to close the door opening whereby the temperature within the car can not be reduced from atmospheric influences.

Further objects of the invention are to provide a car door seal which is simple in its construction and arrangement, strong, durable, efficient in its use, and comparatively inexpensive to set up with respect to the car door.

With the foregoing and other objects in view the invention consists of the novel construction, combination and arrangement of parts as hereinafter more specifically described and illustrated in the accompanying drawings, wherein is shown an embodiment of the invention, but it is to be understood that changes, variations and modifications can be resorted to which come within the scope of the claim hereunto appended.

In the drawings wherein like reference characters denote corresponding parts throughout the several views:—

Figure 1 is a sectional plan, illustrating a sealing means in accordance with this invention for a sliding door.

Fig. 2 is a sectional detail of one side of a car and a car door showing the adaptation to the latter of a seal in accordance with this invention.

Fig. 3 is a front view of entire door jamb and attached strip.

Referring to the drawings in detail 1 de-

notes a laterally movable door body and positioned against the inner face thereof is a compressible member comprising a flexible element 9, which provides a pocket 10, containing the compressible packing 11 which completely fills the pocket. The pocket 10 is rectangular in cross-section. The flexible element 9 is secured to the door body in such a manner as to provide the pocket 10 with closed sides, tops and bottom. The flexible element 9 and packing 11 extend continuously around the inner face of the door body 1, that is to say at the top, bottom and side marginal portions of the inner face of the door body 1.

The side 59 of the car body has an opening 3 and secured to the inner face of the side 59, by holdfast devices 65, is a door jamb 66, having each of its sides, its top and its bottom provided with a strip 67 of any suitable material as shown in Fig. 3. The front face of the strip 67 is corrugated as at 68. The strip 67 is of less width than the width of the pocket 10.

When the door is forced laterally toward the jamb, the corrugated strip or strips 68 will compress the compressible member thereby sealing the door, when the latter is shifted to close the opening.

What I claim is:—

The combination with a door jamb having each of its sides, its top and bottom provided with a strip having its front face corrugated, of a lateral movable door body adapted to be shifted toward said jamb, and a compressible member consisting of a flexible element secured to the inner face of the door body at the top, bottom and side marginal portions thereof, and providing a pocket containing a compressible packing, said member capable of being compressed by said corrugated strip to provide a seal when the door body is closed, said strip of less width than the width of said member, and said pocket being rectangular in cross-section.

In testimony whereof I affix my signature in the presence of two witnesses.

MARTIN THORSEN RELLING.
